UNITED STATES PATENT OFFICE.

WILLIAM T. RICHARDS, OF NEW HAVEN, CONNECTICUT.

MACHINERY EMPLOYED IN THE MANUFACTURE OF COILED-WIRE FERRULES.

Specification forming part of Letters Patent No. 9,262, dated September 14, 1852.

To all whom it may concern:

Be it known that I, WILLIAM T. RICHARDS, of the city and county of New Haven, in the State of Connecticut, have invented a new and useful Improvement in Machinery for Making Wire Ferrules; and I do hereby declare that the following is a full, clear, and exact description of the construction, character, and operation of the same, reference being had to the accompanying drawings, which make a part of this specification, in which—

Figure 1 is a perspective view of the front part of the machine. Fig. 2 is a plan view of an upright section of the same. Fig. 3 is a plan view of the crank which works the die to cut the wire. Fig. 4 is a perspective view of a ferrule made ready for use.

My improvement consists in the use of a mandrel or rod to sustain the helical coil of wire, a clamp worked by a cam to hold the coil while being cut, a semicircular die worked by a crank to cut off the coil, and a gage worked by a lever and cam to throw the severed part off.

I make the frame-work of cast-iron or other suitable material, which consists of a bed-plate, A, and an upright part, B.

Near the outer end of the bed-plate A, I fix a movable stud, C, to which I attach a mandrel or rod, D; onto which the helical coil of wire is passed. As the stud C is capable of being turned round, the inner end of the mandrel D may be swung out so as to slip on the coil a with perfect convenience, and it is steadied by a block, b.

In the center of the lower end of the upright part B, I secure in a proper socket a short mandrel, e, onto which the coil is to be passed (from the mandrel D) a sufficient distance for the length of a ferrule, with a gage, d, to determine the length and to throw off the part of the coil when severed.

In the center of the upright part B, I fit the main slide E, which carries the cutting-die F. This slide E is worked by a crank (like Fig. 3) on the shaft e, by means of connecting-rods f, in the usual way.

In the back or inner side of the main slide E, I fit a secondary slide, g, which carries at its lower end a concave or semicircular clamp or holder, h, Fig. 2, to hold the coil firmly on

the short mandrel e while being cut off by the cutting-die F. This slide g is forced down by the cam G working on the friction-roller i, and is removed or thrown up by the spiral spring H, Fig. 2.

To the back side of the upright part B, I attach a bent lever, I, working on a fulcrum-j, Fig. 2. The upper end of this lever is forced outward by the cam k, which carries the lower end forward, and, by means of the two rods l l, works the gage d to throw the severed piece of the coil from the short mandrel e, and it is thrown back by the spring K, Fig. 2. The length of the ferrule is regulated by the nut m, Fig. 2.

Having constructed and arranged the several parts of the machine, and the wire having been coiled in the usual way, and the coil passed onto the mandrel, (the mandrel resting on the block b and gaged as to its direction by the set-screw n,) I feed the coil forward by hand until it passes onto the short mandrel e up to the face of the guard d. I then revolve the wheel L in the direction indicated by the dart, when the crank on the arbor e will bring down the main slide E, while the cam G will force down the secondary slide g, so as to press the clamp or holder h onto the coil, while the main slide E, continuing to descend, will bring the edge of the cutting-die F over the upper edge of the short mandrel e and cut the wire at right angles to the axis of the coil, so as to completely sever the parts, leaving both ends true and smooth. The cam G will then release the secondary slide g, and the spiral spring H will throw the slide g up to its former position, and the crank, by the continued motion of the wheel L, will raise the main slide E to its former place. At the same time the cam k will, by means of the levers I, force the gage d forward and throw off the piece of coil thus severed, which will fall through the opening at M into a proper receptacle, and the machine will be ready for another operation.

The advantages of my improvements consist in the rapidity and cheapness with which the ferrules are made and the regularity of their forms, as any required quantity can be made of exact size and proportions, even by a child.

I am aware that clamps or holders and cutting-dies have been worked by cranks and by

cams. I therefore do not claim these as such as my invention; but

What I claim as my invention, and desire to secure by Letters Patent, is—

1. The method of cutting the wire at right angles to the axis of the coils, so that the ends of the ferrules will be perfectly true, without wasting any of the stock, by the use of the short mandrel *c*, the clamp or holder *h*, and the cutting-die *F*, when the machine is constructed, arranged, and made to operate substantially as herein described.

2. The combination of the method of cutting the coil, as described above, with the method of supporting the long coil, and of feeding it, and of throwing off the piece when severed, when combined, arranged, and operated substantially as herein described.

WM. T. RICHARDS.
